(57) **CLAIM**

The ornamental design for a catheter connector securement device, as shown and described.

DESCRIPTION

FIG. 1 is a perspective view of a catheter connector securement device embodying my new design, with a catheter secured in the device shown in phantom;

FIG. 2 is a perspective view of the securement device shown in FIG. 1 with the upper shell member in an open position for receipt of a catheter connector;

FIG. 3 is a top view of the open securement device shown in FIG. 2;

FIG. 4 is a top view of the closed securement device shown in FIG. 1;

FIG. 5 is a side view of a first side of the securement device shown in FIG. 4;

FIG. 6 is a side view of a second side of the securement device shown in FIG. 4;

FIG. 7 is an end view of a first end of the securement device shown in FIG. 4;

FIG. 8 is an end view of a second end of the securement device shown in FIG. 4; and,

FIG. 9 is a bottom view of the securement device shown in FIG. 4.

The broken lines in the drawings represent unclaimed environmental subject matter illustrating the design in use and form no part of the claim.
